GLOVE

Pierre Leon Vernhes, Johnstown, N. Y.

Application December 10, 1938, Serial No. 245,002

4 Claims.

(Cl. 2—159)

My invention particularly relates to a glove and to a method of fabricating the same. Heretofore, in the glove industry, it has been customary, when making ladies' gauntlet gloves, for example, to provide a glove blank formed from a sheet of flexible material, such as leather, which comprises portions forming a covering for the hand including the back and front of the fingers and the back and front of the gauntlet portion of the glove, and to overfold the blank along a line extending longitudinally thereof and substantially centrally of the blank. The edges of the blank, therefore, lie in superposed positions and form a side edge of the glove. In finishing the glove, the usual thumb piece is sewn in the thumb opening provided therefor, fourchettes are sewn between the front and back finger-forming portions, and the glove, throughout the entire length thereof, is sewn along its side to fasten the superposed edges of the blank together. In making a gauntlet glove in this manner, the edge of the glove lying along the line upon which the blank is folded must necessarily be straight and, therefore, it has been necessary to produce the flare in the gauntlet by flaring the edges of the blank. Hence, the flare of the gauntlet lies wholly on one side of the finished glove thereby rendering it asymmetrical. Furthermore, the appearance of the side stitching or seam is, generally speaking, undesirable.

It is, therefore, a primary object of my invention to provide a glove comprising integral finger, hand and gauntlet portions which is symmetrical in form and which, additionally, is of such pattern that it provides a better fit, particularly about the wrist, than gloves formed in the customary manner above set forth. Another object resides in providing a gauntlet glove formed from a blank which is so arranged that the glove may be completely sewn without any stitching or seam extending along either side thereof. Another object lies in providing a glove of the foregoing character wherein the blank employed in forming the same is so shaped that substantially no greater waste occurs when a plurality of blanks are cut from a trunk of material than is experienced in cutting glove blanks of the character heretofore employed.

A further object resides in the novel method of fabricating gloves of the character herein contemplated; and, with the foregoing and other objects in view, my invention includes the novel constructions and arrangements of parts and the steps in the method of fabricating gloves,

described below and illustrated in the accompanying drawing, in which—

Fig. 1 is a plan view of a preferred form of glove blank;

Fig. 2 is a plan view of the back of a finished glove formed from the blank of Fig. 1; and

Fig. 3 is a sectional view taken through the glove of Fig. 2 in about the plane 3—3 thereof.

In the drawing, I have illustrated the preferred embodiment of my invention wherein 1 indicates generally the glove blank formed of suitable, flexible material. The central portion of the blank 1 comprises the finger portions 2, 3, 4 and 5 which are adapted to form the fronts of the glove fingers. Contiguous to the finger portion 2 is a finger portion 6, substantially conforming to portion 2, and adjacent said portion 6 is a finger portion 7 which substantially conforms to the finger portion 3. The finger portions 6 and 7 are adapted to be overfolded along the dot-dash line 8 upon the finger portions 2 and 3, respectively, whereby to form the fronts and backs of the glove fingers. Likewise, a finger portion 9, substantially conforming to finger portion 5, lies contiguous thereto and a finger portion 10, which conforms to finger portion 4, lies adjacent the portion 9. Portions 9 and 10 are adapted to be overfolded about the dot-dash line 11 upon the portions 5 and 4 respectively, to form the backs for said finger portions. As illustrated, the blank is slitted, of course, to the correct depth between adjacent finger portions except between the portions 2 and 6 and 5 and 9, respectively, which serve to form the fronts and backs of the first and little fingers.

Beneath the finger-forming portions above described and intermediate the length of the blank is a central portion 12 which lies between the fold lines 8 and 11 and is provided with the usual opening 13 for a thumb piece, the portion 12 forming a covering for the palm of the hand. Contiguous to and along both sides of the portion 12 extend side portions 14 and 15 which comprise the finger-forming portions for the back of the glove and which are adapted to be folded over upon the portion 12 to form the covering for the back of the hand. The free edges of the lateral portions 14 and 15 preferably extend substantially in parallel relationship and, from the points 16 and 17, the sides of the blank preferably diverge to provide the gauntlet forming portion of the glove blank. For purposes of illustration, the edges of the flares so formed on each side of the lower central portion of the blank

are shown as generally sinusoidal or scalloped for decorative purposes.

At the points 16 and 17, the lateral, side portions of the glove blank are slit as indicated at 18 and 19, the slits extending approximately to the lines of fold 8 and 11 and divide the lateral, side portions of the glove blank into the upper, side portions 14 and 15, above described, and the lower, side portions 20 and 21. The portions 20 and 21 are adapted to be overfolded, about the dot-dash lines 22 and 23, respectively, and upon the lower central portion 24 of the blank, which forms the gauntlet covering for the front of the arm and wrist while the portions 20 and 21 are adapted, in part, to form the gauntlet covering for the back of the wrist and arm.

In forming the glove, the lateral portions 14 and 15 of the blank are folded over about the lines of fold 8 and 11 with their free edges in abutting or slightly overfolded relationship. The lateral, side portions 20 and 21 of the gauntlet forming portion of the blank are also folded over and, in order to form a flaring, symmetrical gauntlet, the slits 18 and 19 are opened while maintaining the respective lateral, side portions of the blank, which lie on opposite sides of said slits, substantially in the same plane. In other words, the slits 18 and 19 permit the portions 20 and 21 to be overfolded along lines extending at an angle to the lines of fold 8 and 11 or along the lines of fold 22 and 23 whereby, in part, to form the gauntlet, indicated generally at 25 in Fig. 2, which is flared outwardly from both sides of the glove and is symmetrical.

In overfolding the lateral, side portions of the glove blank in the foregoing manner, the sides of the slits 18 and 19 are spread apart thereby forming substantially V-shaped, oppositely disposed notches. A gore element 26 is sewn within the opening formed between the V-shaped notches and the gore preferably extends between and is stitched to the edges of the overfolded portions 20 and 21, as illustrated. The stitching 27 which fastens the gore element in position may be of a decorative nature.

The meeting edges of the lateral portions 14 and 15 are also sewn together as indicated at 28 and the stitching employed in so doing, as in the case of stitching 27, may also be of a decorative nature and may resemble the stitching employed in forming the decorative ribs 29 on the back of the glove.

Of course, in completing the glove, fourchettes are stitched between the finger-forming portions 55 in the ordinary manner and the usual thumb piece is sewn in the thumb opening 13 therefor.

It will be observed that the integral blank, above described, is of a width substantially sufficient to extend around the hand and the base 60 of the wrist and of a length sufficient to form the desired glove and that the overfolded, lateral side portions are so arranged that the blank, except for sewing in the gore, fourchettes and thumb member, need be sewn only between the 65 base of the wrist to the bottom of the finger-forming portions of the blank. In other words, it is only necessary to stitch along the meeting edges between the points 16 and 17 which, when the blank is folded are substantially coincident, and 70 the bottom of the slit between the middle and third fingers and, of course, this stitching may at the same time serve to decorate the back of the glove. Although I have shown the preferred arrangement wherein the line of stitching, which 75 serves to unite the lateral, side portions forming

a covering for the back of the hand, as extending longitudinally of the glove and generally parallel to the sides thereof, I may, of course, so form the blank that said line of stitching will extend from adjacent the V-shaped notches and gore, as illustrated, to a point between any two adjacent finger-forming portions of the glove.

It will be noted that by forming a glove in the foregoing manner, the slits permit the gauntlet portion thereof to be of symmetrical form because the gauntlet may be made to flare outwardly from each side of the glove substantially to the same degree. This not only produces a pleasing and desirable effect but, by so forming the glove, its fitting qualities are greatly enhanced and the glove may be formed to provide a much better fit about the wrist than gloves of somewhat similar shape but which lack the symmetry of the glove herein described.

It is evident that, in the gloves of my invention, there is an absence of side seams, the appearance of which is undesirable, especially in gloves of high quality, and, it will also be observed that very little waste need be experienced in cutting a plurality of blanks of the character herein described from a sheet or trunk of material.

While I have described my invention in its preferred embodiment, it is to be understood that the words which I have used are words of description rather than of limitation. Hence, changes within the purview of the appended claims may be made without departing from the true scope and spirit of my invention in its broader aspects.

What I claim is:

1. A glove comprising a blank of flexible material having centrally disposed portions forming a covering for the palm of the hand, the front of the fingers and the front of the wrist, and side portions overfolded said central portions and forming a covering for the backs of the fingers and the back of the hand; said side portions being provided near the wrist with slits extending inwardly from the edges thereof substantially to the lines of fold, and having the portions of said blank adjacent said slits spread apart; and a gore secured between the edges of said slits and the edges of said side portions to form a flaring gauntlet for said glove.

2. A glove comprising an integral blank of flexible material forming a covering for the front and back of the fingers, the palm and back of the hand and the front and sides of the wrist; said blank having the edges thereof stitched together along the back of said glove from the base of the fingers to the base of the wrist; said edges being provided with inwardly extending slits in the vicinity of the wrist and the portions of said blank at either side of said slits being spread apart to form V-shaped notches in said edges; and a gore element stitched to said blank along said edges and the edges of said notches to form a flared gauntlet on said glove.

3. Those steps in the method of forming a flared gauntlet on a glove which comprise forming a blank of flexible material of a width substantially sufficient to extend around the hand and the base of the wrist, and of a length sufficient to form said glove, slitting said blank inwardly from the opposite edges thereof substantially at the base of the wrist, opening said slits by bending the material of said blank while maintaining the portions thereof at either side of said slits in substantially the same plane, and securing a gore element in position between said edges and the edges of said opened slits.

4. A glove comprising an integral blank of flexible material forming a covering for the front and back of the fingers, the palm and back of the hand and the front of the wrist and having its edges stitched together along the central portion of the back of said glove from the base of the fingers to the base of the wrist; the edge portions of said blank at the base of the wrist

being provided with oppositely disposed V-shaped notches formed by slitting said edge portions and bending the material of said blank in the plane thereof to open said slits and separate the free edges of said blank; and a gore interposed between and stitched to said edges of said blank and having portions extending into said notches. 5

PIERRE LEON VERNHES.
